UNITED STATES PATENT OFFICE.

JEREMIAH C. FITZGERALD, OF KILBOURN, WISCONSIN, ASSIGNOR TO THE FITZGERALD MANUFACTURING COMPANY, OF KILBOURN, WISCONSIN, A CORPORATION OF WISCONSIN.

SHAFT-HANGER.

1,291,461.

Specification of Letters Patent. Patented Jan. 14, 1919.

Application filed September 12, 1917. Serial No. 190,892.

To all whom it may concern:

Be it known that I, JEREMIAH C. FITZGERALD, a citizen of the United States, and a resident of Kilbourn, in the county of Columbia and the State of Wisconsin, have invented certain new and useful Improvements in Shaft-Hangers, of which the following is a specification.

This invention relates to improvements in a hanger for shafts of the type used in machine shops for transmitting power to machines of various kinds, and it consists in certain peculiarities of the construction, novel arrangement and operation of the several parts thereof, as will be hereinafter more fully set forth and specifically claimed.

The principal object of the invention is to provide a shaft-hanger of an extremely simple and inexpensive construction, which shall be strong, durable, and efficient in operation, and so made that it can be readily mounted in either a vertical or horizontal position, to properly support a shaft, or in other words, can be mounted to depend from a ceiling or elevated support, or to extend upwardly from a suitable support, or if desired, can be mounted on a wall or upright support so as to extend laterally or horizontally therefrom.

Another object of the invention is to provide a shaft-hanger of the above described character, the parts of which shall be so made as to enable them to be adjusted in such a manner as to support the shaft at various distances from the ends of the hanger.

Other objects and advantages of the invention will be disclosed in the subjoined description and explanation.

In the accompanying drawing which serves to illustrate an embodiment of the invention,

Figure 1, is a side view of the hanger showing one form of the construction thereof.

Fig. 2, is a view partly in elevation and partly in section, taken on line 2—2 of Fig. 1 looking in the direction indicated by the arrows.

Fig. 3, is a detached perspective view of one of the supporting bolts for the bearing members for the shaft.

Fig. 4, is a view similar to that shown in Fig. 1, illustrating a modification in the construction of the hanger, and

Fig. 5, is a view partly in section and partly in elevation taken on line 5—5 of Fig.

4 looking in the direction indicated by the arrows.

Like numerals of reference, refer to corresponding parts throughout the different views of the drawing.

In the present instance, the hanger is shown as being supported by an elevated support or ceiling 7, and as depending therefrom, but it will be understood that said support may be a vertical one, and that the hanger may extend laterally or horizontally therefrom, or it may be mounted on a support so as to extend upwardly from the latter. As is clearly shown in Figs. 1 and 4 of the drawing, the hanger includes a U-shaped yoke, which by preference, is made of piping or tubular material.

Referring now to Figs. 1 and 2 of the drawing it will be seen and understood that the members 9 of the yoke 8 lie in parallelism with one another, and that each of said members is provided in its inner wall with a longitudinally extended slot 10, each of which slots is provided at suitable distances apart with enlargements or recesses 11, for the purpose to be presently explained. The free ends of the members 9 are fitted in segmental socket pieces 12, formed on and projected from a base or plate 13 which may be secured to the support 7 by means of bolts 14 extended through suitable openings 15 in said plate. These openings 15 are shown by dotted lines in Figs. 1 and 4 of the drawings as being slots or elongated openings, and by preference are so made.

Each of the members 9 is provided near its free end with a transverse opening for the reception of a bolt 16 which bolts are extended through suitable openings in the socket pieces 12 and in connection with nuts 17 on said bolts, serve to firmly secure the free ends of the members 9 to said socket pieces and base.

Adjustably mounted between the members 9 of the yoke, by means of a pair of supporting bolts 18 is the bearing for the shaft. This bearing, is indicated as a whole, by the reference numeral 19 and consists of a pair of segmental or semi-circular blocks 20 of wood or other suitable material placed with their straight edges in contact with one another to provide an opening 21 for the shaft, and a pair of segmental or semi-circular clips 22 which are located on the outer surfaces of the blocks 20 each of said clips hav-

90

95

100

105

ing at each of its sides an apertured extension 23, which extensions are adapted to contact with one another in pairs, so that the openings therein will register with one another for the reception of portions of the supporting bolts 18, one of which is located in each pair of the extensions 23 and may be adjustably secured therein by means of nuts 24 and 25, one of which nuts is located 5 below the extensions 23 and the other one above said extensions as is clearly shown in Fig. 1 of the drawing. Each of the bolts 18 has at one of its ends a lateral projection 25^a which is flattened as shown in Fig. 3 of 10 the drawing. Each of the blocks 20 of the bearing, is provided on its outer surface about midway between its ends with a depression or recess 26, which depressions are by preference concave in shape. When the 15 blocks 20 are placed in their normal positions the depressions 26 therein will be located diametrically opposite each other to receive the projections 27 with which the clips 22 are provided on their inner surfaces 20 at proper points to fit in the recesses 26 of the blocks 20 of the bearing. By this arrangement it will be seen and understood 25 that as the supporting bolts 18, are screw threaded, a nut 25 may be screwed onto each 30 of said bolts toward the projection 25^a thereon, therefore that portion of each of said bolts opposite its projection 25^a may be passed through the openings in the extensions 23 when another nut 24 may be screwed 35 onto each of the bolts 18 so as to tightly clamp the clips 22 in position on the blocks 20, which by reason of the engagement of the recesses 26 in said blocks with the projections 27 on the clips, the said blocks will 40 be prevented from turning or slipping out of the clips. When thus assembled the projections 25^a on the bolts 18 will project in opposite directions. By placing the bearing in the position shown by dotted lines in Fig. 45 2 of the drawing, it is obvious that the flattened projections 25^a may be inserted into the slots 10 of the members 9 of the yoke, and moved up or down in said slots until they reach a pair of the enlargements 11 in 50 said slots, when it is apparent that by turning the bearing to the position shown by continuous lines in Figs. 1 and 2 of the drawing, the bearing will be supported at approximately the desired point. Should 55 the bearing require further or nicer adjustment, this can be accomplished by turning the nuts 24 and 25 on the supporting bolts 18, in the proper direction to advance or retract the bearing on said bolts.

60 In Figs. 4 and 5 of the drawing, I have illustrated a modification in the construction of the hanger, which consists in omitting the slots 10, see Figs. 1 and 2, and in providing the adjacent walls of the members 9 of the yoke with a series of openings 28 located in

spaced relation with one another and in a longitudinally extended row. In this modification the construction of the other parts of the hanger are identical with those shown in Figs. 1 to 3 inclusive of the drawing, with 70 the exception that the supporting bolts of the modified construction are provided each with a lateral projection 29 to enter the openings 28 in the members 9 of the yoke, which projections are by preference cylindrical in shape as shown. When this modified construction is employed it will be necessary to place the projections 29 on the bolts 18 in the openings 28 of the members 9 of the yoke, before the bearing is assembled 80 or mounted on the said bolt, for it is apparent that the projections 29 could not be inserted into the proper openings 28 therefor, after the parts of the bearing have been mounted on the supporting bolts.

85

As the yoke 8 is detachably secured to the socketed parts 12 on the base 13, it is manifest that the hanger can be employed for supporting a shaft at a point between pulleys mounted on said shaft, by simply detaching the yoke from the base 13, then securing the base at the proper place to a suitable support, then placing the yoke astride of the shaft and securing the ends of the members 9 to the base and then placing the parts of the bearing around the shaft, and then suitably adjusting the bearing.

90

While I have shown the ends of the yoke detachably mounted on a base and prefer to so construct the hanger, yet it is apparent 95 that the base and its socketed members may be omitted and the free ends of the yoke otherwise supported.

95

Having thus fully described the invention, what I claim as new and desire to secure by Letters Patent is:

100

1. A shaft-hanger consisting of a suitably supported bifurcated member and a bearing for the shaft suspended between the prongs of said member, a hooked supporting bolt 110 mounted on each side of the hanger and adjustably and pivotally engaging said prongs.

110

2. A shaft-hanger consisting of a suitably supported bifurcated member and a bearing for the shaft suspended between the prongs 115 of said member, a hooked supporting bolt adjustably mounted on each side of the hanger and adapted for engagement with said prongs at suitable points thereon.

120

3. A shaft-hanger consisting of a suitably supported bifurcated member and a split bearing for the shaft located between the prongs of said member and mounted thereon for longitudinal adjustment with respect to said prongs the said bearing consisting of a 125 pair of cross sectionally curved blocks, each having on its outer surface a depression, a pair of curved clips surrounding said blocks and each provided at its sides with an apertured extension and at its middle with a 130

130

- projection to fit in the depression of the block adjacent thereto, and supporting means located in said apertures and engaging said prongs.
- 5 4. A shaft-hanger consisting of a suitably supported bifurcated member made of tubular material, the prongs of said member each having in its inner wall a longitudinally extended slot provided with spaced apart enlargements, a bearing for the shaft located between said members, and a pair of supporting bolts adapted to fit and operate in said slots and the enlargements thereof and engaging the said bearing at its sides.
- 10 5. In a shaft-hanger, the combination with a base, of a substantially U-shaped member made of tubular material and secured at its ends to the base, the prongs of the U-shaped member having in their adjacent walls longitudinally extended slots provided with spaced apart enlargements, a bearing for the shaft located between the members of the U-shaped member and consisting of a pair of cross-sectionally curved blocks, each of said blocks having on its outer surface a depression, a pair of curved slips surrounding said blocks and each provided at its sides with an apertured extension and at its middle with a projection to fit in the depression of the block adjacent thereto, a supporting bolt having a flattened extension at one of its ends located in each of said slots, each of said bolts being extended through the apertured extensions on said slips, and a nut on said bolts on each side of the extensions of the slips.
- 15 6. A shaft-hanger consisting of a suitably supported bifurcated member made of tubular material, the prongs of said member each having in its inner wall a longitudinally extended slot provided with spaced apart enlargements, a bearing for the shaft located between said members, a pair of supporting bolts having oppositely disposed extensions at one of their ends adapted to engage the means therefor on said prongs and said bolts engaging said bearing at its sides, a nut located on each of said bolts at the sides of the bearing for adjusting the bearing with respect to said bolts.
- 20 7. A shaft-hanger consisting of a suitably supported bifurcated member made of tubular material, the prongs of said member each having in its inner wall a longitudinally extended slot provided with spaced apart enlargements, a bearing for the shaft located between said members, a pair of supporting bolts each having at one of its ends a flattened extension and engaging the said bearing at its sides, and a nut on each of said bolts on each side of its point of engagement with the bearing for adjusting the latter with respect to said bolts.
- 25 8. A shaft hanger comprising in combination a bifurcated member, a split bearing for a shaft pivotally suspended between the prongs of said bifurcated member and vertically adjustable thereon, and means to suspend said bifurcated member, said suspending means being adjustable in a horizontal plane transverse to the axis of said bearing.
